Patent expires November 18, 1962

5 Claims. (Cl. 238—349)

1

This invention relates to means for fixing railway rails to their supporting chairs by means of a resilient wedge.

Various means of this kind have already been proposed. A common feature of many of these is that the chair is provided with a rib, running in the longitudinal direction of the rail, of which one side acts as a guide for the rail in the chair and the other side acts as a part of the guide track into which the resilient wedge is driven. A common feature of most of these devices is also that the resilient wedge is made from a piece of steel plate which is bent through an angle of about 180° in such a manner that it has a more or less hairpin-like section. The wedge is then frequently shaped in such a manner that one of the arms formed by bending the steel plate is longer than the other, this arm being pressed against the base flange of the rail in order to hold this firmly on the sleeper, while the short arm is received in a guide which is formed by the previously mentioned rib and by another rib or the like in the chair which is spaced from the first mentioned rib and parallel to it.

The fastening means of the present differs from the previously known devices in that the guide into which the resilient wedge is driven and the wedge are shaped in such a manner that the pressure against the rail is produced by an upwardly directed pressure exerted by the chair against a part of the resilient wedge. The invention, moreover, enables one to have a fairly free hand with regard to the choice of the pressure to be exerted against the rail, since the effective length of the arm of the resilient wedge which presses against the rail can be chosen without regard to the dimensions of the wedge guide or track itself and in spite of the point of contact between the wedge and the rail remaining the same.

To obtain these results, the fastening device comprises a chair and a resilient wedge and the chair is provided, at least on one side, with a projecting rib which runs along the side edge of the base flange of the rail, which rib acts on the one hand as a guide for the flange of the rail and on the other hand serves for fixing the wedge and is also provided with a rib or groove which is parallel to and spaced from the first-mentioned rib and forms the other side of the guide for the wedge and the resilient wedge is in the form of a plate having a long arm which passes over the rib and extends to the vicinity of the base flange of the rail and abuts against the upper face of the flange and a short arm, formed at an angle of ap-

2

approximately 180° with the long arm, which engages between the two ribs, or between the one rib and the groove in the chair, and, in accordance with the invention, there is provided on the underside of the short arm a pressure foot which runs parallel to the front edge of the arm and at the same distance therefrom as the distance between the two ribs on the chair, or between the one rib and the groove in the chair, which foot bears against the upper side of the chair inside the outermost rib, or in the bottom of the groove in the chair, a part of the said foot or chair where they come into contact being formed as a wedge, so that the introduction of the resilient wedge in the longitudinal direction of the rail between the two ribs or between the one rib and the groove in the chair, effects a tilting movement of the resilient wedge about the point of contact of the short arm against the one rib and causes the other arm to press against the upper side of the base flange of the rail.

In order that the invention may be easily understood and readily carried into effect, two forms of a rail fastening device constructed in accordance with the invention are illustrated by way of example in the accompanying drawing, in which:

Figure 1 shows the chair with the resilient wedge in position and the rail clamped to the chair;

Figure 2 is a plan of Figure 1;

Figure 3 is a side elevation of the resilient wedge itself;

Figure 4 is a side elevation of the wedge shown in Figure 3, and

Figure 5 is a modified form of construction of the wedge.

Referring to the drawing, the numeral 1 in Figures 1, 2, 3 and 4 indicates the chair which, in the form of construction illustrated in these figures, is used for fixing a rail 9 by clamping the base flange 10 of the rail against the chair plate by means of a resilient wedge 3. In the chair there are provided wedge guides 11 into which the wedges 3 can be driven. These guides comprise two ribs 2 which are provided one on each side of the base 10 of the rail and have overhanging upper parts 12 as well as ribs 4 which are arranged parallel to the ribs 2 and laterally to the outside thereof. The chairs can be fastened to the sleepers by means of bolts 8.

The resilient wedge 3 is illustrated separately in Figure 3. It is formed from a steel plate in such a manner that a longer arm 13 and a shorter arm 14 are formed which are at an angle of ap-

proximately 180° or greater with each other. Near the point from which the longer and shorter arms 13 and 14 extend, there is provided, in the form of construction illustrated in Figure 3, a pressure foot 7. The pressure foot 7 is inclined or bevelled off at one end of the wedge in such a manner as to form a wedge surface 6 and a surface 5 at the place where the pressure foot meets the arm 14 as shown in Fig. 4.

When the resilient wedge is to be used it is 10 driven lengthwise into the guide 11 whereby the foot 7 is pressed down against the chair plate 1 when the front end 15 of the short arm 14 bears against the underside of the rib 2 in such a manner that a tilting movement about the point of contact between the front edge 15 of the short arm 14 and the overhanging part 12 of the rib 2 is caused to take place which causes the front edge 16 of the long arm 13 to press against the upper side of the flange 10 of the rail 9.

A particularly advantageous form of construction of the resilient wedge is shown in Figure 5. The wedge illustrated in this figure is made by bending a steel plate into the shape shown whereby the distance between the front edge 15' of the short arm 14' and the pressure foot 7' on the under side of the short arm 14' may easily be made any desired distance. The long arm 13' can then be extended, as shown, in such a manner that the long arm 13' and a part of the short arm 14' contribute towards the resiliency of the wedge.

As will be understood, either form of the fastening device may be modified by omitting the rib 4 or 4' and providing instead of it a groove in the chair the foot 7 being adapted to fit into the groove. It will also be understood that, instead of forming a wedge surface 6 on the resilient wedge 3, a corresponding wedge surface may be formed in the chair alongside the rib 4 or in the bottom of the groove in the case when a groove is employed instead of the rib 4.

We claim:

1. Means for fastening a railway rail comprising a resilient wedge and a chair, said resilient wedge being insertable lengthwise in said chair, a projecting rib on a side of said chair which extends along the side edge of the base flange of the rail and acts on the one hand as a guide for the flange of the rail and serves on the other hand for fixing the wedge in conjunction with a groove in said chair which is parallel to and spaced from the said rib and forms the other side of the guide for said resilient wedge, said resilient wedge being in the form of a plate having a long arm which passes over the said rib in said chair and abuts against the upper surface of the flange of the rail and a short arm connected to said long arm which engages between the said rib on said chair and the said groove in said chair, a pressure foot on the underside of said short arm parallel to the free edge of said short arm and at the same distance from the said free edge as the distance between the said rib on said chair and said groove on said chair, said pressure foot adapted to bear against the upper side of said groove in said chair, said foot being formed where it initially comes into contact with said groove in said chair with a wedge shaped surface, whereby introduction of said resilient wedge in the longitudinal direction of the rail between the said rib and the said groove in said chair causes said resilient wedge to tilt

about the point of contact of said short arm with said rib and said long arm to press against the upper side of the base flange of said rail due to the action of said wedge shaped surface on said pressure foot in said groove.

2. Means for fastening a railway rail comprising a supporting plate, a projecting rib on the upper side of said supporting plate extending along a side edge of the base flange of the rail, the upper end of said projecting rib being bent in a direction away from the rail to form an overhanging portion, said projecting rib forming one side of a guide channel, means spaced from said projecting rib away from the rail and extending parallel thereto forming a second side of said guide channel, a resilient wedge slidably mounted in said guide channel, said resilient wedge comprising a plate member having a long curved arm extending over said projecting rib to 15 the base flange of the rail and a short relatively straight arm, a projection comprising a pressure foot extending below said resilient wedge approximately at the point of juncture of said long and short arms, said pressure foot being wedge 20 shaped at a point in proximity to an end thereof and tapering gradually to a flat reduced depth end portion, the inward end of said short arm abutting against the underside of said overhanging portion and said pressure foot abutting against said second side of said guide channel, the free end of said long arm pressing against the upper side of the base flange of said rail when said resilient wedge is driven lengthwise 25 into said guide channel for causing a tilting movement of said resilient wedge about the point of contact of said short arm with said overhanging portion due to said wedge shaped portion of said pressure foot.

3. Means for fastening a railway rail as claimed 30 in claim 2, said means spaced from said projecting rib comprising a second projecting rib on the upper side of said supporting plate.

4. Means for fastening a railway rail as claimed 35 in claim 2, said resilient wedge being formed from a plate, the end of said long arm being bent through an angle greater than 180° with respect to the short arm to form a resilient elbow joining said arms.

5. Means for fastening a railway rail as claimed 40 in claim 2, said short arm being doubled back upon itself and having the free end portion thereof bent at an angle thereto and forming said pressure foot extending below said wedge, the doubled end portion of said short arm forming 45 said inward end of said short arm contacting said overhanging portion of said projecting rib.
